UNITED STATES PATENT OFFICE.

JOHN LE VALLEY, OF PAINTED POST, NEW YORK, ASSIGNOR TO INGERSOLL-RAND COMPANY, OF JERSEY CITY, NEW JERSEY, A CORPORATION OF NEW JERSEY.

FREE-AIR UNLOADER FOR COMPRESSORS.

Application filed January 12, 1927. Serial No. 160,653.

This invention relates to compressors, but more particularly to a free air unloader for compressors of the type in which plate valves or equivalent devices are disposed in the walls of the cylinder to control the admission and exhaust of air into and from the compressor cylinder.

The objects of the invention are to prevent the up-building of a receiver pressure in excess of that which it is desired to maintain for immediate purposes, and in general, to simplify the construction and reduce the costs of manufacturing and maintaining devices of this character.

Other objects will be in part obvious and in part pointed out hereinafter.

The invention consists of the combination of elements and arrangement of parts having the general mode of operation substantially as hereinafter described and claimed and illustrated in the accompanying drawings, in which—

The figure is a sectional elevation of a portion of the compressor cylinder having the invention applied thereto.

Referring more particularly to the drawing, A represents a compressor cylinder having a piston chamber B in which is disposed a piston C.

Disposed on the end of the cylinder A is a head D having an inlet passage E through which air may be supplied to the piston chamber B and also having a discharge chamber F into which the air compressed by the piston C may be discharged.

In an inner wall G of the head D is formed an opening H to afford communication between the piston chamber B and the discharge chamber F. In the construction shown, a discharge valve mechanism J comprising the usual valve seat K, valve plate L and stop plate O is seated in the opening H to control communication between the said chambers B and F. The valve mechanism J is held firmly in assembled position by a jack screw P screwed through a cover Q which forms a closure for the discharge chamber F.

The air discharged into the discharge chamber F may pass therefrom through a port R in the head D and thence through a suitable conduit S to a receiver tank T of any suitable type.

According to the present invention a hole U in the wall G which affords communication between the piston chamber B and the inlet passage E comprises an enlarged portion V and a portion of smaller diameter W joined in this instance by a tapered surface or seat X adapted to cooperate with a similarly tapered surface Y of the seat Z of an inlet plate valve mechanism b. In addition to the seat Z the inlet plate valve mechanism b also comprises a stop plate c and a valve plate d clamped operatively between the valve seat Z and said stop plate.

The enlarged portion or diameter V of the opening U is preferably of considerably larger diameter than the valve seat Z so that when the said valve assembly b is moved from its normal operative position in a manner to be more fully described hereinafter, a suitable and adequate space will exist between the valve seat Z and the wall of the opening U to permit the free passage of air between the seat X and the tapered surface Y of the valve seat Z.

Suitable and novel means are provided for holding the valve mechanism b in its normal operative position, that is, in the position it is intended to occupy while the compressor is operating under full load conditions. To this end an unloader stem e is disposed slidably through an end wall f of the head D and has a reduced portion g which extends through the valve seat Z and the valve plate d and is screw threaded at its inner end to receive the stop plate c. The outer, or what may be termed the free end h of the unloader stem e is in this instance provided with an annular external groove j for the reception of a slotted washer k which serves as a seat for one end of a coil spring o interposed between the said washer k and the wall f of the head D for holding the valve seat Z firmly against the tapered seat X in the opening U.

In the present instance a guide p is disposed in the wall f of the head D to act as a guide for the stem e. A portion q of the guide p which projects rearwardly of the head D is preferably of such diameter as to form a guide for the spring o and of such length as to extend within a suitable distance of the washer k. In this way when the mechanism b is unseated, the outer end

of the guide *p* will act as a stop to control the distance which the valve mechanism may be moved.

A suitable casing or enclosure is provided 5 for the portions of the stem *e* and the guide *p* which extend rearwardly of the head *D*, as well as for the spring *o*. In the present instance this casing comprises a hollow body *r* seated on the wall *f* and suitably secured thereto by means of screws *s*. The outer end 10 of the body *r* is exteriorly threaded as at *t* for the reception of a correspondingly threaded cap *u* between which and the body *r* is clamped a rubber diaphragm *v* to span 15 the end of the body *r*. The diaphragm *v* in the present instance is supported by and is adapted to act against a diaphragm head *w* supported by the washer *k*. Preferably, a pressure chamber *x* is formed in the inner 20 face of the cap *u* for the reception of pressure fluid to act against the diaphragm *v*.

Pressure fluid is in this instance conveyed to the pressure chamber *x* through a pipe *y* leading from the receiver tank *T* to 25 the pressure chamber wherewith it communicates through a passage *z* in the cap *e*.

Any suitable and well known means may be provided for controlling the admission of pressure fluid from the receiver tank *T* into 30 the pressure chamber *x* whenever it is desired to unload the compressor, or in other words, whenever the pressure in the receiver tank *T* exceeds a value which it may be desirable to maintain. In the drawing, a 35 pressure controlling valve *2* is interposed in the pipe *y* for this purpose. The pressure controlling valve *2* is preferably of the type described in United States Patent No. 1,138,278, granted May 4, 1915 to J. H. 40 Castle and W. G. Rogers to which patent reference may be had for a detail description of the construction and operation of the valve illustrated. The invention, however, is not dependent for its successful operation upon the precise type of controlling 45 valve disclosed and other suitable and well known devices may be substituted for the valve *2* for controlling the admission of pressure fluid to the pressure chamber *x*.

50 During the period that the compressor is operating under full load conditions, the inlet valve mechanism will occupy the position illustrated in the drawings. The admission of air from the inlet passage *E* will 55 then be controlled by the valve plate *d* of the valve mechanism *b* in the usual manner, the valve mechanism *b* being held in this position by the spring *o* which is of ample strength to hold the valve mechanism firmly 60 against the seat *X* unaffected by any forces to which the valve mechanism may be subjected during the normal operation of the compressor. The air thus drawn into the piston chamber *B* will then be compressed 65 by the piston *C* as is of course understood,

and is discharged through the discharge valve *J* into the discharge chamber *F*, thence through the port *R* and through the conduit *S* into the receiver tank *T*. The operation described may continue indefinitely so long 70 as the pressure in the receiver tank *T* does not exceed a certain predetermined value. In the event, however, that the pressure in the receiver tank *T* should exceed that which it is desired to maintain or at which the 75 pressure regulating valve *2* is adjusted to open, the said valve *2* will establish communication between the receiver tank *T* and the pressure chamber *x* to allow pressure fluid to act against the diaphragm *v*. Upon the introduction of pressure fluid into the pressure chamber *x*, the diaphragm *v* will act against the diaphragm head *w* and compressing the spring *o* will move the valve assembly *b* in the direction of the piston 80 chamber *B*, thus establishing a free passage over and around the tapered portion *Y* of the valve seat *Z* between the inlet passage *E* and the piston chamber *B*.

As will be observed the air will be 85 pumped back and forth between the inlet passage *E* and the piston chamber *B* without necessitating the operation of the valve plate *d* and without discharging any air 90 into the discharge chamber *F*. The compressor may continue to operate under these 95 conditions until the receiver pressure has been reduced to a value which will permit the regulating valve *2* to close and again discharge the air from the pressure chamber *x* in a well understood manner. Upon the exhaust of pressure fluid from the pressure chamber *x*, the spring *o* will again react to return the valve mechanism *b* to its 100 normal operative position.

105 I claim:

1. In a compressor, the combination of a cylinder, a head for the cylinder having an inlet passage, said head also having an opening to afford communication between the cylinder and the inlet passage, a valve mechanism seated in the opening to control the opening, a stem reciprocable in the head supporting the valve mechanism, a spring 110 acting against the stem for holding the valve mechanism in normal operative position, and pressure responsive means associated with the stem for actuating the valve mechanism bodily inward towards the cylinder space and out of operative position to 115 permit free and uninterrupted communication around the valve mechanism between the inlet passage and the cylinder.

2. In a compressor, the combination of a cylinder, a head for the cylinder having an inlet passage, said head also having an opening to afford communication between the cylinder and the inlet passage, a seat in the opening, a valve mechanism adapted to rest 120 on the seat, a stem in the head supporting 125

the valve mechanism, a spring acting against the stem to hold the valve mechanism against the seat during the loaded period of the compressor, an unloader body on the head, a cap for the unloader body, and a diaphragm clamped between the body and the cap acting against the stem upon the application of pressure fluid to the dia-

phragm for unseating the valve assembly in an inwardly direction, thus establishing 10 uninterrupted communication between the cylinder and the inlet passage.

In testimony whereof I have signed this specification.

JOHN LE VALLEY.
